UNITED STATES PATENT OFFICE.

CYRUS JAY SELTZER, OF PHILADELPHIA, PENNSYLVANIA, ASSIGNOR TO RHODES LOCKWOOD, WILLIAM N. LOCKWOOD, AND RHODES G. LOCKWOOD, COPARTNERS UNDER FIRM-NAME OF DAVIDSON RUBBER COMPANY, OF BOSTON, MASSACHUSETTS.

ATOMIZER.

SPECIFICATION forming part of Letters Patent No. 700,838, dated May 27, 1902.

Application filed May 3, 1901. Serial No. 58,617. (No model.)

To all whom it may concern:

Be it known that I, CYRUS JAY SELTZER, a citizen of the United States, residing at Philadelphia, in the county of Philadelphia and 5 State of Pennsylvania, have invented a new and useful Improvement in Atomizers, of which the following is a specification, reference being had to the accompanying drawings, in which—

10 Figure 1 is a longitudinal central section of my improved atomizer. Fig. 2 is an elevation showing the atomizer telescoped, the receptacle being indicated within the bulb in dotted lines. Fig. 3 is a plan, upon an enlarged scale, of the nozzle 5. Fig. 4 is a plan view of a cross-section on line A A of Fig. 1, enlarged. Fig. 5 is a plan view of a cross-section on line B B of Fig. 1. Fig. 6 is a longitudinal central section of a simpler form of 15 my improved atomizer. Fig. 7 is a plan view of a cross-section on line C C of Fig. 6.

The object of my invention is to produce an atomizer which shall be portable, of few parts, and so constructed that it may be held in one 20 hand to operate, leaving the other hand free.

25 My atomizer employs a bulb of the ordinary Davidson type, as is common in all atomizers, the bulb having a check-valve for the admission of air. Fitting into the opposite end of the bulb to that in which the check-valve is fixed is a receptacle which has a sliding engagement with the bulb and may be pushed within the bulb or withdrawn from the bulb, but still remain in engagement 30 therewith in telescoping fashion. This sliding receptacle is marked 3, and in Fig. 1 it is shown as having double walls, the inner wall being marked 4, a space being left between the walls when the double-walled receptacle 35 is used. When the double-walled receptacle 40 is not used, as in the simpler form, (shown in Fig. 6,) a passage is formed or secured in the wall of the receptacle, which passage conveys air from the bulb when the bulb is compressed to the upper inner end of the receptacle, where it is discharged. At the upper or

outer end of the receptacle 3 is secured a spraying device.

The above elements constitute an entirely novel arrangement of the parts to perform 50 the function of an atomizer. I will now describe in detail the construction of my atomizer which is illustrated in the drawings.

At the free end of the bulb 1 is inserted the air-inlet check-valve 2. At the other end of 55 the bulb from that in which the check-valve 2 is inserted and secured is a large aperture, in which is secured a ring of metal or hard rubber 6, to which the edges of the aperture in the bulb are secured. Within this ring is 60 fitted a telescoping receptacle 3, which has a sliding engagement with the ring 6, and this receptacle is prevented from being drawn through the ring and out of the bulb by an annulus 7 upon the exterior lower end of the 65 receptacle 3. The upper face of this part 7, fitting against the lower side of the ring 6, forms a tight joint when the telescoping receptacle is drawn to its full extent out of the bulb. The upper end of this receptacle 3 is closed 70 by the screw-cap 8, having a nozzle 9, the upper end of this nozzle having a minute passage 10 for the escape of the atomized liquid. The screw-cap 8 of the receptacle 3 has secured to its under side, in what I consider its 75 best form, an inner wall 4, of glass, hard rubber, or the like. Within the nozzle 9 is secured a pipe 11, which terminates at its upper end in the conical nozzle 5, having small grooves 5^a upon its outer surface, while the lower end of 80 the pipe is within the receptacle. The conical nozzle 5 fits into a counterpart conical seat at the upper inner end of the nozzle 9, and a small aperture 12 at the apex of the conical nozzle 5 permits the escape of fluid passing 85 through the pipe 11 through the aperture 12, registering with the aperture 10. A passage 13 through the bottom of the receptacle 3 allows air to pass from the bulb 1 into the upper interior of the receptacle 3, and when the 90 inner wall 4 is used another passage 14 permits air to pass from the space between the

walls of the receptacle through screw-cap 8 to the upper interior end of the receptacle 3, above the upper end of the inner wall 4.

The operation of the device is as follows:

- 5 The telescoping receptacle having been pulled out to its full length, part 7 forming a fluid-tight joint with the ring 6, the bulb 1 is compressed, thus forcing the air therein contained into the interior of the receptacle 3,
- 10 creating a pressure of air within the receptacle, which presses upon the surface of the liquid contained therein, simultaneously tending to force the liquid contents through the pipe 11, and at the same time forcing a blast
- 15 of air through the grooves 5^a to unite with the liquid rising through the pipe 11. As the liquid passes through the aperture 12 the combined air and liquid issue from the aperture 10 in the form of a spray.
- 20 In Fig. 6 the air-passage, which is shown in Fig. 1 as formed by the aperture 13, the space between the inner and outer walls of the receptacle, and the passage 14, is provided by a pipe, (shown in Figs. 6 and 7,)
- 25 and the passage so formed is marked 13 13^x. The mode of operation is identical in both forms of my atomizer.
- 30 When the atomizer is not in use, the receptacle 3 is pushed back into bulb 1, and a cap 15 may be placed over the nozzle 9 to prevent the escape of the liquid contents of the receptacle. The receptacle in the mouth of the bulb may be given either a fixed engagement therewith, or, in what I consider a better form, a telescoping engagement therewith
- 35

by means of which when the atomizer is not in use the atomizer may be pushed within the bulb.

I claim—

1. An atomizer made up of a bulb; a receptacle fitting into the mouth of the bulb and having a sliding engagement therewith and a passage through its walls communicating at the lower end of the receptacle with the interior of the bulb and opening at its upper end into the upper interior portion of the receptacle to permit the passage of air under pressure from the bulb to the upper interior end of the receptacle when the bulb is compressed; and a spraying device at the free end of the receptacle, having a pipe depending within the receptacle.

2. An atomizer made up of a bulb; a double-walled receptacle, having a space between the walls and an aperture through the outer wall at the lower end thereof and an aperture through the inner wall at the upper end thereof; a spraying device at the mouth of the receptacle, having its liquid-pipe depending within the inner wall of the receptacle; all organized and arranged, substantially as shown and described, to permit the passage of air under pressure from the bulb to the upper interior end of the receptacle, when the bulb is compressed.

CYRUS JAY SELTZER.
